UNITED STATES PATENT OFFICE

2,685,359

METHOD OF HANDLING AND ASSORTING SHEETS

Rollin D. Osgood, Birmingham, Ala., assignor to
United States Steel Corporation, a corporation
of New Jersey

Original application December 3, 1947, Serial No.
789,403. Divided and this application February
16, 1951, Serial No. 211,284

2 Claims. (Cl. 198—33)

1

This invention relates to improved methods of handling and assorting metal sheets immediately following a plating operation.

The present application is a division of my earlier application, Serial No. 789,403, filed December 3, 1947, and assigned to the same assignee, which application issued as Patent No. 2,564,027, August 14, 1951.

The methods of the present invention are especially suited for handling and assorting steel sheets that have been tin plated by hot-dip processes. Therefore the invention is described in connection with a hot-dip tinning line, but it is to be understood that the invention is not necessarily limited to such application.

The usual practice in hot-dip tinning includes passing steel sheets in multiple parallel rows through molten tin metal, hot palm oil and then through a branner, which removes all excess oil and polishes the tinned sheet. The tinned sheets are then transported to an assorting room, where they are visually inspected and assorted as "primes," "menders," and "waste-waste." Prime sheets are counted and stacked for shipment; menders are reprocessed to form primes, while waste-waste sheets are sold as an off grade product.

In usual installations with which I am familiar, operations performed subsequent to tinning are largely manual, and consequently are time consuming and costly. Each sheet is handled individually during inspection and prime sheets are counted and stacked by hand. During tinning, the trailing or list edge of each sheet becomes slightly thicker than the leading edge since a little more tin accumulates at the trailing edge. Consequently the workman who counts and stacks the sheets must stack them with the trailing and leading edges of each few sheets alternated in order to form a uniform stack.

An object of the present invention is to provide improved methods for handling and visually and digitally inspecting sheets subsequent to plating wherein manual operations are substantially eliminated.

A further object of the invention is to provide improved methods of operating a double hot-dip plating line in which inspection of the sheets is preceded by consolidating a pair of rows of plated sheets into a single row with the leading and trailing edges of every other sheet reversed, whereby only one inspector and one inspection apparatus can inspect and assort a double line and the prime sheets are ready for piling evenly.

A further object of the invention is to provide

2

improved methods for continuously assorting sheets as primes, menders, and waste-waste and arranging alternated sheets with the original leading and trailing edges reversed.

5 In accomplishing these and other objects of the invention I have provided improved details of construction, a preferred form of which is shown in the accompanying drawings wherein:

Figure 1 is a top plan view of a portion of a 10 hot-dip tin plating line following the plating equipment and adapted to be operated in accordance with the method of the present invention;

Figure 2 is a side elevational view of the line, partly in section, the view being taken on line 15 II—II of Figure 1;

Figure 3 is an enlarged top plan view of a preferred construction of sheet transfer apparatus;

Figure 4 is an end elevational view of the transfer apparatus in the direction of arrow 4 in Figure 20 3;

Figure 5 is a vertical sectional view of the transfer apparatus taken substantially on line V—V of Figure 3;

Figure 6 is a horizontal sectional view of the 25 transfer apparatus taken substantially on the line VI—VI of Figure 5;

Figure 7 is an electric wiring diagram of the control circuit for operating the transfer apparatus;

Figure 8 is an enlarged top plan view of a 30 preferred construction of inspection apparatus;

Figure 9 is an enlarged side elevational view of the inspection apparatus;

Figure 10 is a vertical sectional view of the 35 inspection apparatus taken substantially on line X—X of Figure 8;

Figure 11 is a vertical sectional view of the drive mechanism for the inspection apparatus taken substantially on line XI—XI of Figure 8;

Figure 12 is a vertical sectional view of the 40 drive mechanism for the inspection apparatus taken substantially on line XII—XII of Figure 11; and

Figure 13 is an electric wiring diagram of the 45 control circuit for operating the inspection apparatus.

Figures 1 and 2 show branner rolls 14 of hot-dip tin plating equipment from which plated sheets S emerge for assorting and stacking. Sheets emerge from the plating equipment in two parallel rows and pass onto parallel horizontal conveyor belts 15 and 16. Said conveyors are supported on a frame 17 and are driven from a horizontal shaft 18 journaled in the lower portion of said frame. Shaft 18 is driven from

branner roll 14 by a chain 19 and drives the conveyors through chains 20 and 21, Figure 3.

The feeding rate is such that sheets on conveyor 15 are spaced by a little more than the length of an individual sheet. A transfer apparatus 22 lifts the sheets individually from conveyor 15 and places them on conveyor 16 within this space to form a consolidated single row of sheets on conveyor 16. The sheets in said single row are spaced at relatively close and substantially uniform intervals. The details of the transfer apparatus are fully described hereinafter.

From conveyor 16 sheets pass onto a conveyor 23, which is formed of a series of transversely spaced parallel belts 24. Said belts are supported on a frame 25, which has rearward rollers 26, intermediate rollers 27 and forward rollers 28 over which the belts pass. The axis of intermediate rollers 27 coincides with the axis of an inspection wheel 29 hereinafter fully described. Conveyor 23 is driven by a motor 30 which is supported on frame 25 and is operatively connected with the forward rollers 28.

From conveyor 23 the sheets traverse a series of conveyors which carry them past reject gates and to a mechanical counter and piler. The gates, counter and piler are of any suitable known construction. The mechanism beyond conveyor 23 is not per se a part of the present invention; hence its construction is not shown nor described in detail.

The operator visually and digitally inspects sheets as they pass inspection wheel 29, where their travel is temporarily arrested. In accordance with known practice, the operator closes a switch as he detects a "mender" sheet and a different switch as he detects a "waste-waste" sheet. Closing said switches operates respective reject gates after a suitable timed interval such that the defective sheet is rejected to the proper group. Inasmuch as time delay mechanism for operating reject gates is known and per se is not part of the present invention, such mechanism is not shown nor described in detail.

The original leading and trailing edges of sheets transferred from conveyor 15 to conveyor 16 are reversed from the corresponding edges of untransferred sheets so that, except for sheets rejected, the original leading and trailing edges of alternate sheets are reversed in the final stack. The rejection of a few sheets does not appreciably affect uniformity of the stack, and any unevenness tends to be compensated, since rejection may come from sheets originating from either row.

The mechanical construction of the transfer apparatus 22 is shown in detail in Figures 3, 4, 5, and 6. The apparatus comprises a fixed frame 32 that straddles conveyors 15 and 16 and their supporting frame 17. Said frame includes uprights 33 and 34 at opposite sides of said conveyors and cross beams 35 and 36 fixed to said uprights and connected by short longitudinal members 37.

Frame 32 supports a magnetic turntable 38 and drive means therefor. As sheets emerge on conveyor 15, they engage and momentarily close a trigger switch 39, which actuates the turntable magnets to lift a sheet from the conveyor. At the same time the drive means for the turntable is actuated, whereupon the turntable automatically rotates through a substantially semi-circular arc and deposits the sheet on conveyor 16.

As shown in Figures 3 and 4, the drive for the turntable includes a motor 40 supported on cross

beams 35 and 36. Motor 40 runs continuously and drives a worm 41, which drives a worm gear 42, Figure 5. The worm and worm gear are mounted within a fixed housing 43 supported above beams 35 and 36 by legs 44 and 45.

Worm gear 42 is fixed to a vertical shaft 46, which carries an annular driving magnet 47 of a magnetic clutch at its lower end. The upper end of shaft 46 carries a pair of slip rings 48 and 49 for conducting current to the driving magnet 47. Driving magnet 47 is thus continuously rotated and, as hereinafter explained, it may be intermittently energized through slip rings 48 and 49. An annular braking magnet 50 is fixed between beams 35 and 36 beneath driving magnet 47 and is axially aligned with shaft 46.

A vertical shaft 51, axially aligned with shaft 46, is journaled in antifriction bearings 52 and 53. Said bearings are fixed to beams 35 and 36 and permit shaft 51 to have limited axial movement. A clutch plate 54 of magnetic material is fixed to the upper end of shaft 51 in the space between driving magnet 47 and the braking magnet 50. Turntable 38 is fixed to the lower end of shaft 51.

Turntable 38 carries electric transfer magnets 55 and 56 in diametrically opposed positions at opposite sides of said shaft. As shown in Figure 4, the lower faces of magnets 55 and 56 are close to the upper faces of conveyors 15 and 16, but the clearance is sufficient not to interfere with sheet movement. In order to lift thin sheets, magnets 55 and 56 preferably extend radially from a point above the center of each sheet and have elongated radially extending poles.

As best shown in Figures 5 and 6, shaft 51 carries a cam ring 57 and slip rings 58 and 59 at its intermediate region between bearings 52 and 53. The cam ring has two segments of increased radius 180° apart, one of which is shown at 60. Said segments operate a cam switch 61 to deenergize magnets 55 and 56 to deposit sheets on conveyor 16. The slip rings conduct current to magnets 55 and 56. The purpose and operation of these elements is more fully explained hereinafter in the description of the electric circuit.

For supporting cam switch 61, frame member 35 carries a fixed bracket 62 on which is supported an arcuately adjustable yoke 63. Said yoke carries switch 61, which has a roller 64 that rides against the surface of cam ring 57, Figure 6. Cam switch 61 is normally closed, but is opened momentarily while roller 64 engages one of the projecting segments 60 of cam ring 57.

Slip ring 58 comprises two substantially semi-circular segments 65 and 66 separated by insulators 67 and 68, Figure 6. Yoke 63 carries a pair of brushes 69 and 70 engaging segments 65 and 66, the brushes preferably being mounted for arcuate adjustment with respect to the yoke. Slip ring 59 is circular and continuous, and yoke 63 carries a brush 71 which contacts slip ring 59.

A downwardly depending boss 72 is fixed to yoke 63 and has a transverse threaded bore. A threaded spindle 73 is journaled in a fitting 74 which is pivoted to bracket 62, as indicated at 75, Figure 6, to permit arcuate movement of the spindle. Said spindle is threadedly engaged within the transverse bore through boss 72 and carries a knob 76 accessible externally of the apparatus. Thus rotation of knob 76 adjusts yoke 63 arcuately about vertical shaft 51.

Figure 7 shows the control circuit for operating the transfer apparatus. The circuit includes

four relays whose coils are indicated at A, B, C, and D. The contacts of each relay are indicated by the same letters with appropriate subscripts. The circuit includes conductors 71 and 78 connected to a suitable outside power source. Preferably a master switch 79 is provided for manually opening and closing the circuit to said conductors.

A conductor 80 is connected across conductors 71 and 78 and contains relay coil C, contacts B1 and cam switch 61. A conductor 81 is connected to conductor 71 and to conductor 80 shunting relay coil C and contacts B1. Conductor 81 contains relay coil A and trigger switch 39 which, as Figure 3 shows, is positioned in the path of sheets on conveyor 15 so that it closes momentarily as each sheet passes on said conveyor.

Closing of the trigger switch energizes relay coil A, since cam switch 61 is normally closed. Energization of relay coil A closes contacts A1 which seals in relay coil A, shunting trigger switch 39. At the same time, contacts A2 close and establish a current path to segment 65 of slip ring 58 via a conductor 82 and brush 69. Transfer magnet 55 is connected between segment 65 and slip ring 59. Brush 71, which contacts slip ring 59, is connected to conductor 78 through a conductor 83. Thus when contacts A2 are closed, the transfer magnet 55 is energized via conductor 71, contacts A2, conductor 82, brush 69, slip ring segment 65, magnet 55, slip ring 59, brush 71, conductor 83 and conductor 78. Magnet 55 thereupon lifts the sheet from conveyor 15.

Closing of contacts A2 also completes a circuit to relay coil B through normally closed relay contacts D1 and through a conductor 84 connected to the conductor 80 intermediate coil C and cam switch 61. Energization of coil B closes contacts B1 in conductor 80 and thereby energizes relay coil C. Energizing coil C closes contacts C1, which seal in coil B via contacts A2 and C1, thus shunting contacts D1.

At the same time, energizing coil C closes contacts C2 which are in conductor 71. The terminus of conductor 71 is connected to a brush 85 that engages slip ring 48 at the top of vertical shaft 46. Said slip ring is connected to the driving magnet 47 and the opposite end of said driving magnet is connected to slip ring 49. The terminus of conductor 78 is connected to a brush 86 that engages slip ring 49. Energization of coil C also opens contacts C3 which are in a conductor 87 which extends between conductors 77 and 78 and contains the braking magnet 50. Thus the driving magnet 47 is energized and lifts clutch plate 54, whereupon shaft 51 and turntable 38 commence to rotate.

Rotation of shaft 51 rotates slip ring 58 in the direction indicated in Figure 7. After said slip ring is rotated a predetermined distance, brushes 69 and 70 both contact the same segment 65, which forms a current path between them. Brush 70 is connected by a conductor 88 to a timer 89. Said timer is connected to relay coil D through a conductor 90 and relay coil D is connected to conductor 78 through a conductor 91. When brushes 69 and 70 both contact segment 65, a circuit is completed through timer 89 and relay coil D via conductor 77, contacts A2, conductor 82, brush 69, segment 65, brush 70, conductor 88, timer 89, conductor 90, coil D, conductor 91 and conductor 78. Timer 89 contains a mechanism which immediately completes the circuit through coil D and holds said circuit

closed for a predetermined interval and then opens the circuit. Inasmuch as such timing mechanism is known and per se does not form a part of the present invention, the details are not shown. Energization of coil D opens contacts D1 and closes contacts D2, the latter sealing in the circuit through timer 89 and coil D.

Continued rotation of shaft 41 moves one of the projecting cam segments 60 to a position 10 where it momentarily opens cam switch 61. Opening this switch breaks the circuit through conductor 80 and thus deenergizes coils A, B, and C, whereupon the contacts C2 open and interrupt the circuit to the driving magnet 47. Contacts D2 remain closed and contacts C3 are closed by deenergization of coil C. Thus the circuit to the braking magnet 50 is closed. The arrangement is such that cam switch 61 opens about 5° before turntable 38 has rotated 180° so that the turntable comes to rest after rotating exactly 180°. Necessary adjustments in the point at which the turntable stops can be made through adjustment of spindle 73, which varies the position of the cam switch with respect to the 180° point.

The transfer magnets are kept energized momentarily after the turntable has stopped. The circuit by which they are energized at this time is via conductor 71, contacts D2, conductor 88, brush 70, segment 65, magnet 55, slip ring 59, brush 71, conductor 83, and conductor 78. As soon as the predetermined interval has elapsed, timer 89 opens the circuit to coil D, which opens contacts D2 and thereby deenergizes the transfer magnets. The magnets thereupon deposit the sheet on conveyor 16. The apparatus is now in position for the opposite transfer magnets 56 to move a sheet from conveyor 15 to conveyor 16 and the cycle of operations just described is 30 repeated, except that magnets 56, segment 66 and the other cam segment 60 are now operative.

Preferably the braking magnet 50 is shunted by a high resistance 92 and a condenser 93, and the driving magnet 47 is shunted by a similar resistance and condenser 94 and 95 respectively. The purpose of these shunts is to prevent arcing when the circuits to the magnets are broken. This type of shunting arrangement is a known device for preventing arcing and hence is not described in detail.

Preferably a push button position switch 96 is connected around trigger switch 39 and cam switch 61 so that the apparatus can be energized manually for testing and adjustment. It is seen that closing switch 96 has the same effect as closing trigger switch 39.

The mechanical details of the inspection wheel 29 are best shown in Figures 9, 10, 11, and 12. Said wheel comprises six sets of radial spokes 98 fixed to hubs 99, the spokes of each set being parallel with each other and spaced 60° from the adjacent set. Hubs 99 are fixed to a horizontal shaft 100 and spaced longitudinally of said shaft so that a set of spokes is positioned 55 between each pair of belts 24 that make up conveyor 23. Intermediate the hubs, shaft 100 carries the rollers 27 over which pass belts 24 of conveyor 23. Shaft 100 is journaled in bearings 101 and 102 fixed to frame 25. Drive mechanism is provided so that each sheet entering the wheel from conveyor 23 momentarily closes a trigger switch 103 and rotates wheel 29 through an angle of 60°.

The sheet that has entered the wheel thereupon is moved to the position shown in full lines

in Figure 10 and its travel temporarily arrested. With the sheet so positioned, the inspector may readily examine the upper surface. The inspector then manually flips the sheet to the position shown in dot-dash lines in Figure 10, feels the sheet and then examines the other surface. Presently conveyor 23 carries another sheet into the wheel, whereupon the wheel rotates another 60°. On one more movement of the wheel, the inspected sheet is picked up by the forward section of conveyor 23 and carried to the piler or diverted by one of the reject gates.

The adjustment of wheel 29 is such that the wheel comes to rest following each 60° advance when the spokes in the forward and rearward positions are horizontal. As shown in Figures 9 and 10, in the position of rest the upper faces of the rearward spokes are slightly below the upper faces of belts 24 of conveyor 23 in order that sheets entering the wheel do not scrape across the spoke faces. Preferably the forward section of conveyor 23 is downwardly inclined at an angle such that the forward section is intermediate two sets of spokes when the wheel is stopped. As the sector of the wheel containing an inspected sheet rotates past the inclined forward section, said section picks up the sheet and the spokes move cleanly away so that again there is no scraping.

Sheets deposited on the downwardly inclined conveyor section tend to slide down said section, and thus to upset timing of the reject gates. In order to prevent such sliding, magnets 104 are arranged underneath the belts of the inclined conveyor section, preferably being permanent magnets and encased in suitable fixed housings 105.

As shown in Figure 10, the intersection of adjacent sets of spokes 98 is preferably at a sharp angle and the faces of the spokes preferably form a substantially plane surface. This arrangement is desirable in order to keep the sheet flat while undergoing inspection so that it does not distort light reflections. Thus the inspector is enabled to determine more accurately whether there are imperfections in the sheet.

The inspection wheel is preferably driven by a magnetic clutch arrangement similar to that for driving the transfer apparatus. The drive is from a motor 106 which is supported on frame 25 and continuously drives speed reducing gears 107 through a suitable coupling, Figure 8. Gears 107 continuously rotate a shaft 108, the inner extremity of which carries an annular driving magnet 109 of the magnetic clutch, Figure 11. A horizontal shaft 110, axially aligned with shaft 108, is journaled in suitable bearings 111 and 112 on frame 25 and has limited axial movement. The outer end of shaft 110 carries a clutch plate 113 adjacent driving magnet 109. An annular braking magnet 114 is positioned adjacent clutch plate 113 on the opposite side from side driving magnet.

Shaft 110 carries a pinion 115 which meshes with a gear 116 on shaft 100 on which hubs 99 of wheel 29 are mounted, Figure 8. Preferably the ratio of pinion 115 and gear 116 is 1 to 6 so that each whole revolution of shaft 110 rotates wheel 29 through an angle of 60°.

Shaft 110 carries a cam ring 117 which has an enlarged sector 118, Figures 11 and 12. A bracket 119 is fixed on a base 120 beneath said cam ring and supports an arcuately adjustable yoke 121. Said yoke carries a normally closed cam switch 122, which has a cam follower 123 riding

against said cam ring. Switch 122 is opened momentarily as the enlarged sector 118 of the cam ring engages cam follower 123.

The mechanism for adjusting yoke 121 includes a threaded spindle 124 which is journaled in a fitting 125 that is pivoted to bracket 119, as indicated at 126, Figures 11 and 12. The yoke has a projecting boss 127 that has a transverse threaded bore that receives the threaded portion of spindle 124. Thus rotation of said spindle adjusts yoke 121 about the axis of shaft 110. This adjustment varies the position at which cam sector 118 opens cam switch 122 and thus controls the angular position at which wheel 29 comes to rest.

The outer extremity of shaft 108 carries slip rings 128 and 129 which conduct current to the driving magnet 109, Figures 8 and 11.

The control circuit for operating the inspection wheel is shown in Figure 13. The circuit includes conductors 130 and 131 connected to a suitable outside power source. Preferably said conductors include a master switch 132 for manually opening and closing the circuit. Conductors 130 and 131 are connected through a conductor 133 that contains trigger switch 103, cam switch 122 and the coil of a relay E. Closing of trigger switch 103 energizes coil E since cam switch 122 is normally closed.

Energization of coil E closes contacts E1 which seal in coil E. Contacts E2 are also closed and complete a circuit to the driving magnet 109 via a conductor 134, a brush 135, slip ring 128, driving magnet 109, slip ring 129, a brush 136, and a conductor 137 to conductor 131. At the same time, normally closed contacts E3 open and thus interrupt the circuit to braking magnet 114. Thus shaft 110 and inspection wheel 29 are set in motion.

Continued rotation of shaft 110 moves cam 117 to a position where its enlarged sector 118 opens cam switch 122, whereupon the circuit to coil E is broken. Contacts E2 open, interrupting the circuit to the driving magnet, and contacts E3 close, completing the circuit to the braking magnet. The adjustment of yoke 121 is such that shaft 110 stops after one complete revolution, which is equivalent to $\frac{1}{6}$ of a revolution of the inspection wheel.

Preferably the driving magnet 109 is shunted by a relatively high resistance 138 and a condenser 139 and the braking magnet 114 is shunted by a similar resistance and condenser 140 and 141 respectively. The resistance and condenser prevent arcing similar to corresponding elements in the transfer apparatus circuit.

Preferably a jog relay J and double pole jog push button switch 142 are provided for rotating inspection wheel 29 by manual actuation when desired. Jog relay J is connected across conductors 130 and 131 in a conductor 143. Switch 142 has a first pair of poles 144 in conductor 143 and a second pair of poles 145 in a parallel conductor 146, which also contains normally closed contacts J1.

Closing of switch 142 completes a circuit to coil E via conductor 146, poles 145 and normally closed contacts J1. Energization of coil E closes contacts E1 which seal in coil E through cam switch 122. Contacts E4 in conductor 143 thereupon close, and poles 144 of switch 142 close at the same time poles 145 close and complete a circuit through jog relay coil J.

Completing this circuit closes contacts J2 which 75 seals in coil J as long as pushbutton 142 is held

closed. When relay coil J is energized, contacts J1 open, breaking the circuit through switch 142 and contacts J1 through coil E. When cam switch 122 opens, coil E is deenergized and opens, stopping the inspection wheel. Thus switch 142 must be opened and reclosed to operate the inspection wheel manually another notch and another spoke.

From the foregoing description it is seen that the method of the present invention consolidates multiple rows of sheets from the plating equipment into a single row. The original leading and trailing edges of alternate sheets in the single row are reversed so that the sheets can be stacked uniformly as they come from the row. Consolidation of the multiple rows enables inspection and assorting to be conducted from a single station without interrupting continuous movement of the line. Thus the transfer step and the inspection step cooperate and form a novel combination that makes possible continuous assorting and stacking of sheets from a multiple line without additional handling.

While I have shown and described but a single embodiment of the present invention, it is apparent that modifications may arise. Therefore, I do not wish to be limited by the disclosure set forth but only by the scope of the appended claims.

I claim:

1. In the handling of hot-dip tin plated sheets which emerge from tinning equipment, the leading edges of all of said sheets at the start being thinner than the trailing edges thereof, a method of assorting and uniformly piling prime sheets comprising arranging all of said sheets as they emerge from the tinning equipment in a closely spaced single row, reversing the leading and trailing edges of alternate sheets from their original position as they are arranged in said single row, conveying said single row of sheets past an in-

spection station, conveying the inspection sheets from said station toward a prime sheet piler, diverting defective sheets observed at said station from the row ahead of said piler, and piling the remaining prime sheets at said piler with the thinner and thicker edges of adjacent sheets in the resulting pile reversed except for missing defective sheets.

2. In the handling of hot-dip tin plated sheets which emerge from tinning equipment in two parallel rows, the leading edges of all of said sheets at the start being thinner than the trailing edges thereof, a method of assorting and uniformly piling prime sheets comprising consolidating the two rows of sheets into a continuous closely spaced single row, reversing the leading and trailing edges of alternate sheets from their original position as they are placed in said single row, conveying said single row of sheets past an inspection station, conveying the inspected sheets from said station toward a prime sheet piler, diverting defective sheets observed at said station from the row ahead of said piler, and piling the remaining prime sheets at said piler with the thinner and thicker edges of adjacent sheets in the resulting pile reversed except for missing defective sheets.
